UNITED STATES PATENT OFFICE.

FRANK R. LEE, OF LEADHILL, ARKANSAS.

TAPER ATTACHMENT FOR LATHES.

SPECIFICATION forming part of Letters Patent No. 724,592, dated April 7, 1903.

Application filed June 14, 1902. Serial No. 111,664. (No model.)

To all whom it may concern:

Be it known that I, FRANK R. LEE, a citizen of the United States, residing at Leadhill, in the county of Boone and State of Arkansas, 5 have invented new and useful Improvements in Taper Attachments for Lathes, of which the following is a specification.

My invention relates to improvements in taper attachments for lathes, and contem- 10 plates the provision of a taper attachment susceptible of quick and easy application to ordinary turning-lathes and one of which while very simple and inexpensive in construction is efficient and reliable in operation and is 15 possessed of a considerable range of adjustment.

With the foregoing in mind the invention will be fully understood from the following description and claims when taken in con- 20 junction with the accompanying drawings, in which—

Figure 1 is a plan view of a portion of a lathe with my improved taper attachment properly applied thereto; Fig. 2, a transverse 25 section taken in a plane at one side of the lathe-carriage; Fig. 3, a transverse section taken in the plane indicated by the broken line 3 3 of Fig. 1, and Fig. 4 a detail section taken on the broken line 4 4 of Fig. 2.

Similar letters of reference designate corresponding parts in all of the views of the drawings, referring to which—

A A are the longitudinal bars or shears of a lathe-bed; B, a carriage movable longitudinally of the lathe on the bars A; C, a tool-head movable transversely of the lathe on the carriage, and D a cross-feed screw, through the medium of which the tool-head may be moved transversely by the turner when de- 35 sired. These parts may be and preferably are of the ordinary well-known construction, the screw D being susceptible of disengagement or disconnection from the tool-head when it is desired to use my improved taper attach- 40 ment, which I will now proceed to describe.

In the preferred embodiment of my invention the taper attachment comprises cross-bars E, each of which is provided at an intermediate point of its length with a curvilinear 45 slot a and at its ends with clamping-plates b and bolts and nuts c d, through the medium of which it may be adjustably fixed on the

bars A of the lathe-bed, a taper-bar F, ex- 55 tending between the bars E and having a longitudinal slot e extending the major portion of its length, bolts f, extending through the slots a of bars E and the end portions of the bar F and serving in conjunction with nuts g to adjustably fix the bar F with respect to the bars E and the lathe-bed, and 60 means fixed with respect to the tool-head C and having a portion disposed and movable in the slot e of bar F. This means is preferably a clevis G, which straddles the carriage B and tool-head C and is fixed to opposite sides of the latter by bolts g and is provided with a depending projection h, movable in the slot e of bar F.

It will be appreciated from the foregoing that my improved attachment is susceptible 70 of ready application to an ordinary turning-lathe without involving alteration of any of the parts of the lathe and is adapted to be as readily disconnected and removed from the lathe when desired.

The interposition of the bars E between the bars or shears A of the lathe-bed entails arranging the bar F between said bars or shears A; but this is an advantage rather than an objection, since it conduces to the compact- 80 ness of the lathe.

In the practical operation of the lathe equipped with the improved attachment the bar F is adjustably fixed at the angle desired from the line of movement of the carriage B, 85 and then after the work is properly mounted in the lathe and the tool-head C is released from the cross-feed screw D the lathe is started, and the carriage B is moved longitudinally of the lathe by the turner rotating the 90 shaft I, journaled in the carriage, which shaft is equipped with a gear J, intermeshed with a rack K on the lathe-bed. When the carriage B is thus moved longitudinally, the projection h of the clevis G moving in the slot e 95 of bar F will cause the tool-head C to move transversely of the lathe and result in the production of a tapered piece of work.

Notwithstanding the advantages of my improved attachment as pointed out in the foregoing, it will be seen that the attachment is simple and inexpensive in construction and embodies no delicate parts such as are liable to get out of order after a short period of use.

I have entered into a detailed description of the construction and relative arrangement of the parts embraced in the present and preferred embodiment of my invention in order to impart a full, clear, and exact understanding of the same. I do not desire, however, to be understood as confining myself to such specific construction and arrangement of parts, as such changes or modifications may be made in practice as fairly fall within the scope of my claims.

Having described my invention, what I claim, and desire to secure by Letters Patent, is—

15. 1. An attachment for lathes comprising cross-bars adapted to be arranged between the shears of a lathe, and having clamping-plates and bolts at their ends for fixing them on said shears, a taper bar extending between 20 and connected to the cross-bars, a clevis for straddling the carriage and the tool-head of the lathe; said clevis having a depending portion engaging the taper bar, and bolts

bearing in said clevis and arranged to bear against and fix the clevis to the tool-head of 25 the lathe.

2. The combination in a lathe, of the bed having longitudinal bars or shears, cross-bars secured between said shears, a taper bar extending between and connected to said cross-bars, a carriage movable longitudinally of the lathe on the bed, a tool-head movable transversely of the lathe on the carriage, a clevis straddling the carriage and tool-head, and having a depending portion engaging the 30 taper bar, and bolts bearing in said clevis and bearing against the tool-head so as to fix the clevis thereto.

In testimony whereof I have hereunto set my hand in presence of two subscribing witnesses.

FRANK R. LEE.
